UNITED STATES PATENT OFFICE.

CHARLES D. WRIGHT, OF ADRIAN, MICHIGAN.

DESIGN FOR AN INVERTED GAS-LAMP.

45,921.

Specification for Design.

Patented June 9, 1914.

Application filed April 16, 1914. Serial No. 832,393. Term of patent 3½ years.

To all whom it may concern:

Be it known that I, CHARLES D. WRIGHT, a citizen of the United States, residing at the city of Adrian, in the county of Lenawee and State of Michigan, have invented a new, original, and ornamental Design for an Inverted Gas-Lamp, of which the following is a specification, reference being had to the accompanying drawing, forming part thereof.

The figure is a perspective view of an inverted gas lamp, showing my new design.

I claim:

The ornamental design for an inverted gas lamp, as shown.

CHARLES D. WRIGHT
